US00D345137S

United States Patent [19]

Thomas

[11] Patent Number: Des. 345,137

[45] Date of Patent: ** Mar. 15, 1994

[54] **POWER SUPPLY FOR A PROGRAMMABLE CONTROLLER**[75] Inventor: **Sherman G. Thomas**, Earlysville, Va.[73] Assignee: **GE Fanuc Automation North America, Inc.**, Charlottesville, Va.[**] Term: **14 Years**[21] Appl. No.: **639,996**[22] Filed: **Jan. 11, 1991**[52] U.S. Cl. **D13/110; D13/162**

[58] Field of Search 361/380, 383, 391, 392, 361/393, 394, 395, 399, 415; D13/123, 162, 164, 184

[57] **CLAIM**

The ornamental design for a power supply for a programmable controller, as shown and described.

DESCRIPTION

FIG. 1 is a left side elevational view of a power supply for a programmable controller showing my new design. The broken line showing of the conventional multi-pin connector is included for informational purposes only and forms no part of the claimed design;
FIG. 2 is a front elevational view thereof;
FIG. 3 is a right side elevational view thereof;
FIG. 4 is a rear elevational view thereof;
FIG. 5 is a bottom plan view thereof;
FIG. 6 is a top plan view thereof; and,
FIG. 7 is a rear and lower left perspective view thereof.

FIG. 1FIG. 2FIG. 3FIG. 4FIG. 5FIG. 6

FIG. 7
